HIRAM TYLER, OF GAINES, NEW YORK.

Letters Patent No. 63,118; dated March 19, 1867.

IMPROVEMENT IN PUMP-VALVES.

The Schedule referred to in these Letters Patent and making part of the same.

TO ALL WHOM IT MAY CONCERN:

Be it known that I, HIRAM TYLER, of Gaines, in the county of Orleans, and State of New York, have invented a new and improved Pump; and I do hereby declare that the following is a full, clear, and exact description thereof, which will enable others skilled in the art to make and use the same, reference being had to the accompanying drawings, forming part of this specification, in which—

Figure 1 is a vertical central section of my invention.

Figure 2 a detached and enlarged central section of a valve pertaining to the same.

This invention relates to a new and improved double-acting pump, and it consists in a novel arrangement of valves and water passages, and in an improved construction of the valves, as hereinafter fully shown and described, whereby the pump is rendered very efficient in its operation, the parts not liable to get out of repair or become deranged by use, and the pump capable of being used either submerged or above the level of the water to be raised or forced up.

A represents the cylinder of the pump. B, the piston fitted therein, and C the piston-rod. These parts may be of usual construction, and therefore do not require a minute description. D D' represent two tubes, which are parallel with the cylinder A, D being the suction, and D' the force tube. In fig. 1, the pump is represented constructed with a view of being submerged, the water passing into tube D through holes *a* in its side, the bottom or lower end being closed. The tube D' has a pipe E attached, which extends up to the top of the well. The piston B is operated by a brake or lever, F. The suction tube D communicates with the cylinder A by means of two horizontal tubes, G G', one at the upper and the other at the lower part of the cylinder and tube, and within these tubes G G', valves H H' are placed, opening inward, or in a direction towards cylinder A. The tube D' communicates with the cylinder A by means of two similar tubes I I', provided with valves K K', opening outward, or towards the tube D', as shown clearly in fig. 1.

From the above description it will be seen that when the piston B is rising, the valve H' in the tube G' opens, while the valve K' in the tube I' closes, and the water is drawn into the lower part of cylinder A, underneath the piston, as indicated by the arrows 1, while the water in the cylinder A, above the piston B, is forced through valve K in tube I into the upper part of tube D' and up through the pipe E, the valve H, in tube G, being closed. When the piston B descends, the valve H' in tube G' closes, and the water below the piston is forced through valve K' in the tube I' into the tube D' and up through the pipe E, while the valve K in the tube I closes, and the valve H in tube G opens, to admit water into the cylinder above the piston. Thus it will be seen that the pump is double acting, or throws a continuous stream; and it will further be seen that the pump may be used above the surface of the water to be raised by having a suction pipe attached to the lower end of the tube D. The construction of the valves constitutes an important feature of the invention, as the valves of a pump are very liable to get out of repair, and frequently cause a great deal of trouble and inconvenience. L represents the valve-stem, which is fitted in suitable guides b b, and is allowed to slide freely therein, the guides being attached to the annular piece of metal M, on which the seat c of the valve is formed, as shown clearly in fig. 2. N is the valve, through the centre of the inner side of which the rod or stem L passes, and is secured by a nut, d, the valve being allowed to work or play on the rod or stem in the same way as if it were connected by a ball and socket-joint, so that it may conform or adjust itself to the seat c. This kind of valve, as ordinarily constructed, is very liable to work imperfectly, in consequence of the great difficulty in adjusting the valve N to the rod or stem L in a plane at right angles therewith, and parallel with the seat c, and as the valve and its stem are allowed to turn freely, the former will not, except in very rare instances, always fit snugly to its seat; but, by having the valve fitted on its rod or stem, as shown, so that it may work or play on the rod or stem, and adjust itself to its seat, the valve will always work perfectly.

Having thus described my invention, I claim as new, and desire to secure by Letters Patent—

The valve N, attached to the end of the sliding-rod L by means of the nut d, so as to permit the said valve to play on the rod, as herein described; piece M, and guides b b, when all are constructed and arranged as herein set forth.

The above specification of my invention signed by me this 15th day of August, 1866.

HIRAM TYLER.
